US0D1060303S

(12) **United States Design Patent** (10) **Patent No.:** **US D1,060,303 S**
(45) **Date of Patent:** **** Feb. 4, 2025**

(54) **HEADPHONES**

(71) Applicant: **Besing Technology (Shenzhen) Co., Ltd.**, ShenZhen (CN)

(72) Inventor: **Hongxia Chen**, ShenZhen (CN)

(73) Assignee: **Besing Technology (Shenzhen) Co., Ltd.**, ShenZhen (CN)

(**) Term: **15 Years**

(21) Appl. No.: **29/969,837**

(22) Filed: **Oct. 24, 2024**

(30) **Foreign Application Priority Data**

Aug. 30, 2024 (EM) 015070891-0001

(51) **LOC (15) Cl.** **14-01**

(52) **U.S. Cl.**

USPC **D14/205**

(58) **Field of Classification Search**

USPC D14/205, 206, 207, 217, 221, 223, 225; D24/106, 173, 174

CPC . H04R 1/08; H04R 1/10; H04R 1/105; H04R 1/1016; H04R 1/1033; H04R 1/1066;

(57) **CLAIM**

The ornamental design for a headphones, as shown and described.

DESCRIPTION

FIG. 1 is a top perspective view of a first embodiment of headphones, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is shown in an alternate configuration;

FIG. 10 is a top perspective view of a second embodiment of headphones;

FIG. 11 is a bottom perspective view thereof;

FIG. 12 is a front view thereof;

FIG. 13 is a rear view thereof;

FIG. 14 is a left side view thereof;

FIG. 15 is a right side view thereof;

FIG. 16 is a top view thereof;

FIG. 17 is a bottom view thereof; and,

FIG. 18 is shown in an alternate configuration.

The broken lines in the drawings illustrate the portions of the headphones, which form no part of the claimed design.
